FLUID CONTROL MECHANISM

Harry W. Link, Philadelphia, Pa., assignor, by
mesne assignments, to American Engineering
Company, Philadelphia, Pa., a corporation of
Pennsylvania

Application October 28, 1933, Serial No. 695,602

9 Claims. (Cl. 103—38)

This invention relates to fluid control mechanisms, and more particularly to fluid control mechanisms for pumps of the variable stroke reversible discharge type.

One object of the present invention is to provide a control mechanism including power means for adjusting the stroke of a pump of the stated character in either direction, and retaining the pump in adjusted position until the pressure delivered thereby exceeds a predetermined value, at which time automatic means functions to render said power means ineffective thereby permitting the pump to assume a neutral position.

Another object is to provide a control mechanism for pumps of the stated character involving a fluid motor for adjusting and holding the pump on stroke, and automatic means associated with said motor and connected to the pressure delivered by said pump which functions when the pressure exceeds a predetermined value to bypass the fluid of said motor thereby rendering the motor ineffective.

A more specific object is to provide a control mechanism of the stated character for fluid systems including a fluid motor and a pump for operating the same, and having manual means associated with the pump for placing the same on stroke in either direction, and a followup mechanism for adjusting the pump to neutral when the motor has been operated a predetermined amount, and automatic bypass means associated with said motor for rendering the latter ineffective, when the pressure in the system exceeds a predetermined value.

Other and further objects will become apparent as the description of the invention progresses.

Of the drawings:

Fig. 1 is a plan view of a pump and motor unit showing the control mechanism for the pump.

Fig. 2 is a sectional elevational view of an hydraulic press.

Fig. 3 is an end view taken substantially along line 3—3 of Fig. 1.

Fig. 4 is a sectional elevational view of the control motors for the pump.

Fig. 5 is a sectional plan view taken substantially along line 5—5 of Fig. 4, and

Fig. 6 is a sectional view taken through a shuttle valve constituting one of the elements of the control mechanism.

Referring to the drawings, numeral 1 indicates generally a pump and motor unit comprising a variable stroke reversible discharge pump 2, driven by an electric motor 3. Pump 2 is of the

general type shown and described in the United States Patent No. 1,077,979 to which reference may be had for a full disclosure thereof.

In the present instance the pump 2 is employed for actuating an hydraulic press 4 including a cylinder 5 having a ram 6 operating therein. The ram 6 is operatively associated with a mold 7 into which the material to be formed is placed. Fluid from pump 2 is conveyed to cylinder 5 through pipes 8 and 9, respectively, the former of which communicates with the upper end of cylinder 5 while the latter communicates with the lower end of said cylinder. Thus, when pump 2 is so adjusted as to discharge fluid under pressure through pipe 8, ram 6 is forced downwardly and the fluid in the annular chamber between piston 6 and cylinder 5 is returned to the pump through pipe 9. It also follows that when the discharge of pump 2 is reversed fluid under pressure will enter the cylinder 5 of the hydraulic press 4 through the pipe 9 and suction will be applied at the upper end causing the fluid to return to the pump through pipe 8, and the fluid acting against the enlarged portion 10 of ram 6 causes the same to move upwardly to normal position. Cylinder 5 is provided with an annular flange 11 at the lower end thereof, which is adapted to engage the enlarged portion 10 of ram 6 when the latter has been moved to its lower limiting position. Cylinder 5 is also provided with an inwardly extending boss 12 at the upper end thereof which acts as a stop for the ram 6 when the latter has been moved to its upper limiting position.

The control mechanism comprising the present invention is designated generally by the numeral 13, and includes a fluid motor 14 secured to a framework 15 provided on the casing of pump 2. Motor 14 is actuated by a small pilot pump 16, mounted on a framework 17 also secured to the casing of the pump 2. Pump 16 is also of the variable stroke, reversible discharge type shown and described in the aforementioned United States Patent No. 1,077,979. As shown in Figs. 1 and 3, a lever 18 is pivoted at one end to a bracket 19 extending laterally from pump 16. Lever 18 is guided for movement between the upper edge 20 of framework 17 and a cover plate 21, and its movement in either direction is limited by a pair of stops 22 and 23 mounted in the flanges 25 and 26 respectively, of framework 17. A rod 26 is pivoted to lever 18 intermediate the ends of the latter, and extends through a pair of guide blocks 27 and 28 secured to framework 17. The free end of rod 26 is pivoted to a link 29 intermediate

the ends of the latter as shown in Fig. 1. Loosely mounted on rod 26, and abutting the inner face of guide block 27, is a spring seat 30. A similar spring seat 31 is also loosely mounted on rod 26 and which abuts against the inner face of guide block 28, and a coil spring 32 extends between these spring seats. Enlarged portions 33 and 34 extend through guide blocks 27 and 28 and the inner ends thereof abut against spring seats 30 and 31 respectively. Thus spring 32 is compressed when lever 18 is swung in either direction. Spring 32 is provided for the purpose of centering lever 18, as will appear more fully hereinafter. The lower end of link 29 is pivoted to one end of a link 35, the other end of which is pivoted to the stroke adjusting mechanism 36 of pump 16. The upper end of link 29 is pivoted to one end of a link 37, the other end of which is pivoted to a crosshead 38 of motor 14. Motor 14, as shown more particularly in Fig. 5, comprises a main body portion 39 having a series of cylindrical bores 40, 41 and 42 provided therein for receiving pistons 43, 44 and 45 respectively, the cross sectional area of piston 44 being substantially equal to the combined cross sectional areas of pistons 43 and 45. Pistons 43 and 45 engage a crosshead 46, while piston 44 engages a crosshead 38, as shown in Fig. 5. Crossheads 38 and 46 are connected by a pair of tie rods 47 and 48 guided for reciprocation in cylinder body 39. Cylinders 40 and 42 are connected by means of a passage 49 provided in casing 39 as shown in Figs. 4 and 5. Cylinder 42 is connected to pump 16 by means of a pipe 50, while cylinder 41 is likewise connected to pump 16 through a pipe connection 51. It therefore is seen that when pump 16 has been adjusted so as to deliver pressure through pipe 50, fluid under pressure will enter cylinders 42 and 40, thereby actuating pistons 45 and 43 to the left (Fig. 5), causing crossheads 38 and 46 to move to the left, and likewise that when pump 16 has been so adjusted as to deliver fluid pressure through pipe 51 piston 44 will be operated to the right, thereby causing crossheads 38 and 46 to also move to the right.

Referring to Figs. 1 and 3, a substantially vertical lever 52 is pivotally connected at the upper end thereof to a pair of links 53 which links in turn are pivotally connected to crosshead 46. The lower end of lever 52 is pivoted to a bracket 54 secured to the casing of pump 2. One end of a link 55 is pivoted to lever 52 intermediate the ends of the latter, the other end of which being pivotally connected to the stroke adjusting mechanism 56 of pump 2. It therefore is seen that when pressure is applied to motor 14 through the pipe connection 50, pump 2 will be placed on stroke in one direction, and when fluid pressure is applied to the motor through pipe connection 51 pump 2 will be placed on stroke in the opposite direction.

Referring more particularly to Figs. 3 and 4, a second motor 57 is secured upon cylinder body 39 of motor 14 in any suitable manner. Also mounted upon cylinder body 39 and secured to motor 14 by tie rods 62 and 63 is a bypass valve housing 58, as shown in Fig. 4. Fluid motor 57 comprises a cylinder 59 having a piston 60 operating therein, one end of which extends through a gland 61 provided at the inner end of said cylinder. As shown in Fig. 4, the valve stem 64 of a bypass valve 65 is secured at one end to piston 60. A crosshead 66 is slidably mounted on valve stem 64 and the upper and lower ends thereof are provided with apertures through which tie rods 62 and 63 respectively, extend. Crosshead 66 forms an abutment for one end of a coil spring 67 encircling valve stem 64, the other end of which abuts against a collar 68, which in turn abuts against the projecting end of piston 60, as shown in Fig. 4. Valve housing 58 is provided with a pair of chambers 69 and 70 which are separated by a partition 71 having an opening therein through which the reduced portion 72 of valve stem 64 extends. The right hand side of partition 71 (Fig. 4) is formed with a seat for the inner end of valve 65. Fluid motor 57 is connected to the pressure developed by pump 2 through the medium of a pipe connection 73 leading from a shuttle valve 74. Shuttle valve 74 is provided with a pair of fittings 75 and 76 to which are secured a pair of pipe connections 77 and 78 respectively. The inner ends of fittings 75 and 76 are provided with seats for the plunger 74' of valve 74. The other ends of pipes 77 and 78 are connected to fittings 79' and 80' which communicate respectively with pipes 8 and 9 leading from pump 2. It therefore is seen that when pump 2 is delivering fluid pressure through pipe 8 the plunger 74' of shuttle valve 74 will be moved to the right (Fig. 6), thereby permitting fluid to flow through pipe 77, pipe 73, and into the cylinder 59 of fluid motor 57. It is also seen that when pump 2 is adjusted so as to deliver fluid pressure through pipe 9, the plunger 74' of shuttle valve 74 will be actuated to the left (Fig. 6), thereby permitting fluid to flow through pipe 78, pipe 73 and into cylinder 59 of motor 57.

Referring more particularly to Figs. 1, 3 and 4, pipes 50 and 51 are respectively connected to chambers 69 and 70 of valve housing 58 by a pair of pipes 79 and 80. Owing to the fact that the end portion 81 of valve 65, and the annular shoulder formed by the reduced portion 72 of valve stem 64 are equal in area, the pressure communicated to chamber 69 through pipe 79 has no effect upon the valve 65. As stated hereinbefore, fluid motor 57 is connected to the pressure delivered by pump 2 at all times, and consequently when this pressure exceeds the tension of spring 67 piston 60, and consequently valve 65, will be moved to the right, thereby unseating the latter and permitting the fluid to bypass through chambers 69 and 70, and inasmuch as chambers 69 and 70 are connected, respectively, to cylinders 40, 42 and 41 through pipes 79, 80 and 50, 51, the pressures in said cylinders will now be equalized. When this occurs pump 2 will adjust itself to neutral position and no further pumping action occurs. In pumps of this type it is well known that a certain force is required to maintain the same on stroke and that due to the centrifugal force of its rotating cylinder body it will assume a neutral position when this force is removed. Thus when pump 2 assumes a neutral position lever 18 will also assume a normal position intermediate stops 22 or 23 by virtue of the centering spring 30.

As shown in Figs. 1 and 3, a pair of relief valves 82 and 83 are provided in pipes 50 and 51, respectively, to prevent damage to the parts in the event that abnormal pressures should be developed by pump 16. The fluid discharged through relief valves 82 and 83 is delivered to the interior of pump 2 through pipes 84 and 85 respectively.

The operation of the mechanism just described is briefly as follows. The material to be formed is first placed in mold 7. The operator then grasps lever 18 and swings the same to the right 75

(Fig. 1). By this action of lever 18 link 29 will fulcrum about its pivotal connection with link 37 thereby causing link 35 and the stroke adjusting mechanism 36 of pump 16 to move to the right. When this occurs pump 16 will deliver fluid pressure through pipe 50 causing fluid to enter cylinders 42 and 40 of motor 14 thereby causing pistons 45 and 43 operating therein to move to the left (Fig. 5). By this action crossheads 38 and 46 will also move to the left (Figs. 3 and 5) and to the right (Fig. 1), causing lever 52, and consequently the stroke adjusting mechanism 56 of pump 2, to move to the left. Pump 2 is now so adjusted as to apply pressure to pipe 8 and suction to pipe 9, thus piston 6 of the hydraulic press 4 will move downwardly against the material to be formed in the mold 7. Upon movement of crossheads 38 and 46, in this manner, link 37 will also move to the right (Fig. 1) and through its connection with link 29 which now fulcrums about its pivotal connection with rod 26 causes the link 35 and stroke adjusting mechanism 36 of pump 16 to move to the left, thereby adjusting the pump 16 to neutral position. Pistons 43 and 45, and consequently the stroke adjusting mechanism 56 of pump 2 will be held in adjusted position due to the pressure in cylinders 40 and 42. Accordingly, fluid under pressure will continue to be delivered through pipe 8 and into the upper end of cylinder 5 of press 4, causing the piston 6 therein to continue its downward travel. When the piston 6 engages the material to be formed in the mold 7 considerable resistance is encountered and consequently the pressure developed by pump 2 will gradually increase. The spring 67 associated with fluid motor 57 is adjusted to correspond with the maximum pressure required to compress the material in the mold 7. Consequently, when the pressure exceeds this predetermined value piston 60 of motor 57 will move to the right (Fig. 4) thereby unseating valve 65. When this occurs fluid from cylinders 40 and 42 will bypass to cylinder 41 through pipe 50, pipe 79, chambers 69 and 70, pipe 80, and pipe 51, thereby equalizing the pressures acting on pistons 40, 42 and 41. Thus the pressure in cylinders 40 and 42 which holds the crossheads 38 and 46 and the stroke adjusting mechanism 56 of pump 2 in position is reduced and the pump is now permitted to adjust itself to normal ineffective position in a well known manner. When the pump assumes its normal position the movement of the stroke adjusting mechanism will be communicated through link 55 and lever 52 to crossheads 38 and 46 causing them, as well as pistons 43, 45 and 44 to move to normal position. This movement is communicated to rod 26 through links 37 and 29, causing lever 18 to move to normal position. Lever 18 will assume a position midway between stops 22 and 23 by virtue of the centering spring 32. This movement of lever 18 to normal position indicates to the operator of the machine that the pressing operation on the material formed in mold 7 is completed. He then again grasps lever 18 and swings it to the left. When this occurs the stroke adjusting mechanism 36 of pump 16 will be moved to the left causing the pump 16 to be placed on stroke in the opposite direction. Pump 16 will now deliver fluid pressure to pipe 51 causing piston 44 of motor 14, and consequently crossheads 38 and 46 to move to the right (Figs. 3 and 5). When this occurs lever 52, and consequently the stroke adjusting mechanism 56 of pump 2 will be moved

to the right, causing pump 2 to deliver fluid under pressure to pipe 9. Piston 6 of hydraulic press 4 now moves upwardly away from the material formed in the mold 7. Upon movement of crossheads 38 and 46 to the right pump 16 will be actuated to neutral position through link 37 and link 29, the latter of which now fulcrums about its pivotal connection with rod 26 thereby causing the stroke adjusting mechanism 36 of pump 16 to move to the right (Fig. 1) to normal ineffective position. Pump 2 will be retained on stroke owing to the pressure in cylinder 41 until piston 6 of the hydraulic press 4 engages the boss 12 at the upper end thereof. When this occurs the pressure developed by pump 2 will rapidly increase until it exceeds the tension of spring 67. Inasmuch as pump 2 is delivering pressure through pipe 9, this pressure is communicated to the cylinder 59 of motor 57 through pipe 18, shuttle valve 74, and pipe 73, and when the pressure exceeds the tension of spring 67 valve 65 will be moved to the right causing fluid to bypass from cylinder 41 to cylinders 40 and 42 through pipe 51, pipe 80, chambers 70, and 69, pipe 79, and pipe 50, thus releasing the pressure in cylinder 41 and permitting the pump to return to neutral position. Pistons 44 and 43, 45, and crossheads 38 and 46 of motor 14 will also return to neutral, and through the movement of link connections 37 and 29, rod 26 will cause lever 18 to move to neutral position where it will again be centered by spring 32.

By this construction it is seen that pump 2 may be placed on stroke in either direction any amount between no stroke and full stroke position, depending upon the extent of movement of lever 18. After the lever 18 is adjusted in the manner just described, a power mechanism functions to place the pump 2 on stroke where it is retained by the power mechanism until the pressure delivered thereby exceeds a predetermined value, when the pump is permitted to assume its normal ineffective position. Thus the operation of the device is out of the control of the operator once the lever 18 has been adjusted. This construction is highly desirable, especially in connection with devices for forming materials in molds where the materials are formed by subjecting them to predetermined pressures.

While the embodiment herein described is admirably adapted to fulfill the objects primarily stated, it is to be understood that it is not intended to limit the invention to the embodiment herein shown since it may be embodied in other forms, all coming within the scope of the claims which follow.

What is claimed is:

1. In a device of the class described, the combination with a variable stroke reversible discharge pump, of power means for adjusting the stroke of said pump and retaining it in adjusted position, means for conditioning said power means for operation, and automatic bypass means associated with said power means for rendering the latter ineffective when the pressure delivered by said pump exceeds a predetermined value.

2. In a device of the class described, the combination with a variable stroke reversible discharge pump, of means for adjusting the stroke of said pump, said means comprising a fluid motor, a pilot pump for operating said motor, and manual means for adjusting the stroke of said pilot pump, followup means associated with said pilot pump and said motor which renders

- said pilot pump ineffective when the motor is operated in either direction, and automatic bypass means associated with said motor for rendering the latter ineffective when the pressure delivered by the pump first named exceeds a predetermined value.
3. In a device of the class described, the combination with a variable stroke reversible discharge pump, of means for controlling the stroke and direction of discharge of said pump, said means including a fluid motor having a plurality of pistons operating therein, a variable stroke reversible discharge pilot pump for actuating said fluid motor, manual means for conditioning said pilot pump for operation, and followup means for rendering said pilot pump ineffective when said motor has been operated a predetermined amount, and automatic bypass means for rendering said motor ineffective when the pressure in said pump first named exceeds a predetermined value.
4. In a device of the class described, the combination with a variable stroke reversible discharge pump, of control means for placing said pump on stroke in either direction, said control means comprising a fluid motor, a pilot pump for actuating said motor, and manual means for conditioning said pilot pump for operation, bypass means for rendering said motor inoperative when the pressure in said pump first named exceeds a predetermined value, said bypass means comprising a valve, a fluid motor for operating said valve, means connecting said last mentioned fluid motor to the pressure delivered by said pump, said connecting means including a shuttle valve whereby the pressure delivered by said pump in either direction is effective to actuate said bypass valve.
5. In a device of the class described, the combination with a variable stroke reversible discharge pump, of a control means for regulating the stroke and direction of discharge of said pump, said control means comprising a fluid motor having a plurality of pistons operating therein, a pair of interconnected crossheads operatively associated with said motor, some of said pistons being adapted to engage one of said crossheads, and another of said pistons being adapted to engage the other of said crossheads, a pilot pump for actuating the pistons of said motor, manual means for controlling the operation of said pilot pump and followup means operatively connecting one of said crossheads to said pilot pump, whereby when the pistons of said motor have been operated a predetermined distance determined by said manual means said followup mechanism will operate to render said pilot pump ineffective.
6. In a device of the class described, the combination with a variable stroke reversible discharge pump, of control means for regulating the stroke and direction of discharge of said pump, said control means comprising a fluid motor having a plurality of pistons operating therein, a pair of crossheads operatively associated with said motor, some of said pistons being adapted to engage one of said crossheads, and another of said pistons being adapted to engage the other of said crossheads, a pilot pump for operating said fluid
- motor, means for conditioning said pilot pump for operation, means for connecting one of said crossheads with the stroke and discharge regulating device of said first mentioned pump, and followup mechanism connecting the other of said crossheads with the stroke adjusting mechanism of said pilot pump whereby, when the pilot pump actuates the pistons of said motor a predetermined amount to place the first mentioned pump on stroke said followup mechanism will render ineffective said pilot pump.
7. In a device of the class described, the combination with a variable stroke reversible discharge pump, of stroke and direction of discharge regulating mechanism for said pump, fluid power means for actuating said mechanism in either direction, said fluid means comprising a motor having a plurality of pistons operating therein, a pair of crossheads operatively associated with said motor, a pilot pump for actuating the pistons of said motor, some of the pistons of said motor being adapted to engage one of said crossheads, and another of said pistons being adapted to engage the other of said crossheads, manual means for conditioning said pilot pump for operation, means connecting the stroke and direction of discharge mechanism of said first mentioned pump with one of said crossheads, followup mechanism for connecting the other of said crossheads with the stroke adjusting mechanism of said pilot pump, whereby when said fluid motor has operated the stroke adjusting mechanism of said first mentioned pump a predetermined distance said pilot pump will be rendered inoperative, and automatic means associated with said motor for releasing the pressure therein when the pressure delivered by said first mentioned pump exceeds a predetermined value.
8. In a device of the class described, the combination with a variable stroke reversible discharge pump, of power means for adjusting the stroke of said pump and retaining it in adjusted position, means for conditioning said power means for operation, automatic by-pass means associated with said power means for rendering the latter ineffective when the pressure delivered by said pump exceeds a predetermined value, and adjustable means controlling the operation of said bypass means.
9. In a device of the class described, the combination with a variable stroke, reversible discharge pump, of means for adjusting the stroke of said pump, said means comprising a fluid motor, a pilot pump for operating said motor, and manual means for adjusting the stroke of said pilot pump, followup means associated with said pilot pump and said motor for rendering said pilot pump ineffective when the motor is operated a predetermined distance in either direction, automatic bypass means associated with said motor for rendering the latter ineffective when the pressure delivered by the pump first named exceeds a predetermined value, and adjustable means associated with said bypass means for conditioning the same for operation at different predetermined pressures.

HARRY W. LINK.
